UNITED STATES PATENT OFFICE.

HENRY JONES, OF FORT WILLIAMS, ONTARIO, CANADA.

SWITCH.

1,185,408.

Specification of Letters Patent.

Patented May 30, 1916.

Application filed February 27, 1915. Serial No. 11,008.

To all whom it may concern:

Be it known that I, HENRY JONES, a subject of the King of Great Britain, residing at Fort Williams, in the Province of Ontario, Dominion of Canada, have invented new and useful Improvements in Switches, of which the following is a specification.

The present invention relates to an electric circuit maker and breaker, and mechanism for operating the same.

In carrying out my invention it is my purpose to provide an electric circuit, such as a lamp circuit, with a circuit maker and breaker operated by a motor whereby the lamps may be lighted at a determined time and likewise extinguished at a determined time.

It is also my purpose to construct a device of this character in the nature of a clock having a revoluble disk thereon and hands rotated by the operating mechanism of the clock, one of said hands being so connected to the revoluble disk as to engage an electric contact when the disk is rotated a predetermined distance upon the face of the clock to light the lamp circuit, the second hand being also arranged to engage with the disk in such a manner as to again actuate the contact to break the circuit and extinguish the lamps.

It is also my aim to provide a device of this character which shall embody the desirable features of simplicity in construction, cheapness in manufacture and positiveness in operation.

With the above and other objects in view, the improvement resides in the construction, combination and arrangement of parts set forth in the following specification and falling within the scope of the appended claim.

In the drawings: Figure 1 is a front elevation of the improvement, Fig. 2 is a rear elevation of the same, Fig. 3 is a longitudinal section approximately on the line $x-x$ of Fig. 1. Fig. 4 is a perspective view of the circuit maker and breaker, the lamp circuit being shown in diagram, and Fig. 5 is a perspective view of one of the hands.

Referring now to the drawings in detail the numeral 1 designates a motor, the same, in the present instance, being in the nature of a spring motor, the mechanism being inclosed in a suitable frame comprising a back plate 1 and a front plate 2, the said plates being spaced from each other through the

medium of the usual spacing sleeves through which pass the ordinary bolts.

The outer plate 2 is provided with the usual face or dial 3, the main shaft 4 of the motor mechanism extending centrally through the said face 3 for a suitable distance, and arranged upon the projecting end of the shaft 4 is a disk 5, the same having radially disposed marks or depressions 6 arranged upon its outer face adjacent its periphery. The disk 5, is also provided with a plurality of apertures or small openings 7, one of which being disposed adjacent each of the indicating marks 6. The indicating marks as well as the apertures 7 are twelve in number, corresponding with the hours indicated by the figures upon the dial 3. A sleeve 8, of the ordinary construction, is arranged over the main shaft 4, and extends through the central opening in the disk 5.

With my improvement I employ two hands indicated by the numerals 8 and 9 respectively. Both of these hands are of a substantially similar construction, each having one of their ends provided with a sleeve 10 which frictionally engages with the projecting end of the shaft 4, while the inner faces of each of the hands, adjacent their opposite ends, are provided with laterally extending pins or studs 11, and each of the said studs is adapted to be inserted through one of the apertures 7 in the disk 5, and to project a suitable distance beyond the inner face of the said dial. It should be stated that the dial 5 is disposed a suitable distance to the front of the face 3.

Arranged upon the frame of the motor, above the intermeshing wheels thereof is the shaft 12 of the circuit maker and breaker. The shaft is journaled in suitable openings in the front and rear plates of the motor, and the said shaft has secured thereon a sleeve 13 provided with a spring arm 14' which normally contacts with the inner face of the outer plate 2, of the motor, and serves to prevent the accidental rotation of the shaft 12. Arranged upon the outer end of the shaft 12, which projects beyond the front face of the motor is a wheel 14, the same having its periphery provided with radially projecting pins 15, and one of these pins is disposed within the path of contact with one of the studs 11 of one of the hands 8 or 9.

The shaft 12 of the circuit maker and

- breaker is insulated from the frame of the motor, and has its end which projects beyond the rear plate 1 of the motor frame, provided with a circuit breaker disk 16. 5 This disk has its rear face provided with a laterally extending pin 17, and if desired, the central portion of the disk may be formed of some insulating material.
- The numeral 17' designates an ordinary 10 lamp circuit which may be provided with a hand operated switch 18. One of the wires, indicated by the numeral 19 of the circuit 17' has its end provided with a wiper switch 20 which rests upon the periphery of the circuit breaker disk 16, the second wire 21 of the circuit being also provided with a switch arm 22 which is arranged within the path of contact of the pin 17 of the disk 16.
- The shaft 12 is of a sufficient length to 20 arrange the disk 16 a suitable distance away from the rear of the motor frame, so that the winding handle of the spring shaft of the motor may be manipulated without interfering with the disk 16, and the operation 25 of the device may be briefly described as follows: When it is desired that the lamps of the circuit 17 shall be lighted at a certain hour and the determined time is, say, one hour distant, the pin 11 of the hand 30 8 is passed through the aperture 7 opposite the figure 1 upon the dial 3. It will be apparent that when the motor revolves the disk and consequently the hand 8, the pin 11 will engage with one of the pins or teeth 35 15 upon the wheel 14, rotating the shaft 12 a predetermined distance, the said distance being sufficient to bring one of the contact fingers 17 of the circuit breaker disk 16 into engagement with the spring switch 40 22. This completes the circuit 17', and consequently lights the lamps of the circuit.

The lamps are to remain lighted a predetermined period, say, for four hours. The hand 9 is rotated upon the disk 5 until its pin 11 is passed through the opening or 45 aperture 7 opposite the figure 5 upon the dial 3. When the disk 5 is rotated the pin 11 of the hand 5 will engage with one of the pins or teeth 15 of the wheel 14, rotating the shaft 12, in the same direction. 50 The rotation of the shaft will also rotate the disk 16 to bring the pin 17, previously engaging with the spring switch 22, beyond the said switch. This movement will cause the switch 22 to lie between the contacted pin and the adjacent pin 17 of the disk, thus breaking the circuit and of course extinguishing the lamps. 55

Having thus described the invention, what I claim is:

In a device for the purpose set forth, a motor, a disk having spaced apertures on the shaft of the motor, a hand loosely carried by the shaft and having a stud to be passed through one of the apertures of the disk, a shaft journaled on the motor frame, a wheel having radially extending pins on the shaft and the said pins being disposed for contact by the stud of the hand, a disk on this shaft, said disk having spaced laterally extending pins, and a member having switch arms one of which resting in the periphery of the disk and the other disposed normally between two of the pins and in the path of contact with said pins. 70 75

In testimony whereof I affix my signature in presence of two witnesses.

HENRY JONES.
